UNITED STATES PATENT OFFICE.

ANSON J. BENTLEY, OF NILES, OHIO.

ICE-MAKING APPARATUS.

1,406,167.

Specification of Letters Patent. Patented Feb. 14, 1922.

Application filed November 8, 1919. Serial No. 336,559.

To all whom it may concern:

Be it known that I, ANSON J. BENTLEY, a citizen of the United States, and a resident of the city of Niles, county of Trumbull, 5 and State of Ohio, have invented an Improvement in Ice-Making Apparatus, of which the following is a specification.

This invention relates to apparatus employed in the manufacture of artificial ice 10 and it particularly relates to the freezing cans which receive water to be frozen and which are placed in or near a freezing solution.

One of the objects of this invention is to 15 provide a fluid conductor to be assembled with the freezing can; the conductor, preferably a tube, will form a conduit for the fluid, generally air under pressure, to the bottom of the freezing can. This fluid after passing 20 into the can will rise and thereby keep the impurities in the water agitated so that they will not be included in the ice.

Another and important object of this invention is to assemble the tube with the 25 freezing can so that the tube does not enter the can to any substantial extent and is held against the side of the can so that it is not injured during the formation of the ice and the removal of the ice cake.

30 This invention possesses many other and advantageous features, some of which, together with the foregoing, will be set out more at length in the following description wherein will be outlined in full that form 35 of the invention which has been selected for illustration in the drawings accompanying and forming a part of the present specification.

The attached drawing which forms a part 40 of this application illustrates one of the preferred embodiments of the invention, wherein:

Figure 1 is a perspective view of the can.

Figure 2 is a section thereof taken below 45 the reinforcing band at the top of the can.

Figure 3 is a section taken on the line 3—3 of Figure 5.

Figure 4 is a section in part of one of the sides, the base, and the conducting means, 50 showing one method of attaching the conducting means or tube to the side, and

Figure 5 is a section in part of the base, of one of the sides, the tube, and one of the 55 protecting members, showing an additional method of attaching the conducting means to the side.

In ice making apparatus, referring particularly to the container for forming cakes of ice, there has been employed a means for conducting a fluid from the top of the can 60 to the bottom thereof and allowing the exit of the fluid into the water to be congealed thereby keeping the impurities in the water moving so that they will not be included in the resulting cake of ice. Several various 65 means have been employed in order to conduct this fluid to the bottom of the can. It is not advisable to have the conducting means or tube enter the freezing can but to have an opening in the side thereof through 70 which the fluid may pass directly into the water to be congealed. In the practical use of these ice freezing cans, it is advantageous to have a substantially smooth interior surface so that the ice will have a uniform shape 75 and can be easily removed from the can.

The invention herein disclosed and described provides for the attachment of a conducting means or tube in the opening in the side of a freezing can. The tube itself does not extend into the can in all instances but it may extend therein for the purposes of forming a positive attachment but not to make a substantial projection in the can which would allow the formation 85 of a shoulder in the ice cake which would render difficult the removal of the cake of ice from the can.

Referring to the figures, there is shown in Figure 1 the freezing can 1 having the base 2 and the reinforcing flange 3 at the top. This flange may be an additional member or may be an extension of the sides turned over upon themselves. A portion of a channel 4 formed in one of the sides is illustrated at 90 the top of the can and this channel receives the tube 5 which forms a conduit for the liquid from the top of the can to the lower part thereof. Protecting members 6 are provided to assist in maintaining the tube in 95 position, if desired, and to protect it. These protecting members may be spot welded into position or may be riveted or attached by any other desirable means. In Figure 2 the tube is shown as nesting in the channel 4. 100 This channel extends from the top of one of the sides toward the bottom thereof as is clearly illustrated in Figures 1, 4 and 5, and is bent outward at its lower end so that the full width of the 110 bottom portion will conform with the contour of the base. There is an opening in

the lower part of the channel to receive the tube which forms the conduit for the fluid. It is advantageous in apparatus of this character to have the fluid enter the can near the bottom and since the can is set in a freezing solution it becomes necessary to conduct the fluid from the top of the can to the bottom and the tube employed may be any of the well-known designed pipes or tubes. The 10 tube as selected is illustrated herein as being circular. The top of the tube may be tapered on its inner surface to receive a plug or there may be on its external surface near the top thereof annular beads for assisting 15 in holding a flexible hose in positive contact with the end of the tube, or any other well-known attaching means may be employed. Preferably the tube should not enter the can as the formation of the ice would 20 then provide the formation of shoulders in the ice which would prevent the easy removal of the ice cake. In the illustrations herein made, the freezing can is of rectangular design. This invention, however, 25 is not limited to such a design and differently shaped cans may be employed. When a rectangular freezing can is employed, it may be advantageous to have the fluid pass across the longest diameter of 30 the can and for this reason the tube is shown as being assembled in a channel formed in one of the narrower sides. A channel and a tube assembled therein may be employed in each or any of the sides if desired, or a channel 35 without the tube may be formed in any of the sides.

The general formation of the base of the freezing can is partially shown in Figure 4 wherein the edges of the base are of U-shape, having the sides 7 and 8. The interior part of the base 9 is higher than the lower end of the U-shaped part. The sides of the can are received by the U-shaped portion and are held therein by any holding means, as 40 for instance, rivets 10 illustrated in this figure. The lower end of the channel is shown as formed in a side 11. Preferably, the channel is of uniform depth and extends from the top of the side to the bottom at a point 45 for instance, just above the interior portion 9 of the base, and is then bent outward to conform to the general contour of the base and to be received by the U-shaped portion.

An opening 12 is made in the side 11 for 50 the reception of the fluid conducting tube 5. In this instance the end of the tube is bent and is received by the opening 12. If desired, the end of the tube may be tapered and the hole 12 reamed to fit therewith, the 55 object being to form a fluid tight joint in a simple manner. Preferably the joint between the tube and the can is soldered not

only for the purpose of rendering the joint fluid tight but also to assist in holding the tube in position. The tube may be soldered 65 to the can at various points along its length or for its full length. The opening 12 is preferably of uniform diameter as illustrated in Figure 4, but it may be tapered as described above.

A modification of the method of attaching the tube to the freezing can is shown in Figures 3 and 5. The method herein employed is to have the opening 12 of non-uniform diameter and to have the end of 75 the tube 5 tapered so that it enters the opening 12 and the projecting part of the tube turned back against the inner part of the side 11 thereby causing the end of the tube to be firmly held in contact with the side. 80 The peaning of the end of the tube against the side is performed in such a manner as to create the smallest shoulder possible on the interior surface of the side 11 and thereby preventing any substantial shoulder from 85 being formed in the ice cake which would prevent the easy removal of the cake of ice. It might not be necessary when using this method of attachment to employ solder and such an attachment would not be a substantial entrance of the tube into the interior of the freezing can.

It will be understood that the embodiment of the invention herein described and shown in the accompanying drawings may be variously modified, and that the present invention is susceptible of different embodiments. Insofar as such modifications and embodiments of the invention come within the scope of the following claims they are considered 100 to be within the scope of the invention.

I claim:

A freezing can having a channel formed vertically in one wall thereof, said channel being of identical cross section from the top of the can to a point adjacent the base when said channel is provided with an end wall contacting substantially with the base of the can near the edge thereof, an air tube provided with an integral elbow at one end for insertion in a hole formed in the inner wall of the channel adjacent the lower end thereof, said tube being fastened in said channel and extending from end to end thereof and being securely attached thereto 110 at the lower end to form an air tight conduit opening to the interior of the can, whereby air may be forced through said tube to agitate water in said can during the freezing operation.

In testimony whereof, I have signed my name to this specification this fifth day of November, 1919.

ANSON J. BENTLEY.
